CLAIM

An ornamental design for a shoe covering, as shown and described.

DESCRIPTION

FIG. 1 is a front perspective view of a new design for shoe covering that has a series of internal portions textured with a loop fastener and a pair of straps connected with a hook and loop fastener. The small dashed lines represent stitching which forms part of the claimed design. The small dashed parallel lines represents double stitching which forms part of the claimed design.

FIG. 2 is a rear view thereof showing a zipper to the left side of a centrally located heel loop;

FIG. 3 is a front view thereof;

FIG. 4 is a left side view thereof;

FIG. 5 is a right side view thereof;

FIG. 6 is a top view thereof;

FIG. 7 is a bottom view thereof showing four textured portions in the left front, left rear, right front and right rear that are all the texture of a loop fastener; and,

FIG. 8 a front perspective view thereof showing the new design for shoe covering on top of a show in large broken lines. The large broken lines are not part of the claimed invention that are shown for environmental purpose.

The solid line showing illustrates the claimed features within the design for the claimed article of manufacture, while the large broken lines illustrates the non-claimed features within the design for the claimed article of manufacture. The shading with single lines is provided to illustrate contour only and is not an indication of texture, gloss, etc. However, the shading in FIGS. 1 and 7 that is shown with curled lines does show texture.
